UNITED STATES PATENT OFFICE.

FREDERICK W. HEIDELBACH, OF COEUR D'ALENE, IDAHO.

FIRELESS HOVER.

1,070,805.

Specification of Letters Patent.

Patented Aug. 19, 1913.

Application filed August 8, 1912. Serial No. 714,044.

To all whom it may concern:

Be it known that I, FREDERICK W. HEIDELBACH, a citizen of the United States, residing at Coeur d'Alene, in the county of Kootenai and State of Idaho, have invented certain new and useful Improvements in Fireless Hovers; and I do declare the following to be a full, clear, and exact description of the invention, such as will enable others skilled in the art to which it appertains to make and use the same.

This invention relates to improvements in fireless hovers.

One object of the invention is to provide a hover of this character having an improved arrangement of heating and heat retaining mechanism, and means for supporting the same in operative position whereby a uniform heat is maintained and evenly distributed and in which crowding of the chicks is obviated.

Another object is to provide a fireless hover which will be simple, strong, durable and inexpensive in construction, efficient and reliable in operation and which may be used with equal advantage in or out of doors.

With these and other objects in view, the invention consists of certain novel features of construction, and the combination and arrangement of parts as will be more fully described and claimed.

In the accompanying drawings; Figure 1 is a perspective view of my improved hover showing the manner in which the same is arranged for very small chicks; Fig. 2 is a similar view of the hover with the chick retaining band removed; Fig. 3 is an enlarged central vertical section of the hover as arranged in Fig. 1; Fig. 4 is a perspective view of the frame for supporting the curtain and heat retaining pillow of the hover. Fig. 5 is a detail vertical section of a portion of the hover, showing the preferred construction and arrangement of the heating mechanism; and Fig. 6 is a plan view of the same with the heat retaining pillow removed. Fig. 7 is a detail side view of the lamp and a portion of the current conducting cord showing the knob for adjustably supporting the lamp.

In the embodiment of the invention I provide a supporting frame 1 comprising upper and lower inner rings 2 and 3 which are of suitable size and an outer upper ring 4 of considerably larger size than the inner

rings and which is arranged around and disposed in the same horizontal plane with the upper inner ring 2. The upper inner ring 2 is connected to the lower ring by standards 5 and 6 while the outer ring is secured to and spaced from the upper ring by radially disposed rods 7 and 8. The upper ring 2 and the standard 5 and supporting rod 7 are formed from a single piece of wire which is first bent intermediate its ends to form the ring 2, said ends being twisted together and one of the same being extended laterally to form the supporting rod 7, while the other end is bent downwardly at right angles to the rod 7 and forms the standard 5. The lower end of the standard 5 is carried around and securely clenched to one side of the lower ring 3 as shown at 9. The outer end of the rod 7 is fastened in a loop 10 formed in one end of the outer ring 4 as shown. The lower ring 3 and the standard 6 and supporting rod 8 are also formed of one piece or rod, one end of which is bent around and secured to form the ring and is then bent upwardly at right angles to the ring to form the standard 6. At the upper end of the standard 6 the rod is bent or coiled around the upper ring 2 at a point diametrically opposite to the twisted portion of the upper ring as shown at 11 and the end of the wire is then bent outwardly and extends radially from the ring 2 at right angles to the standard 6 and in line with the rod 7. The end of the rod 8 is engaged with an eye or loop 12 bent in this side of the outer ring 4 and has its extremity coiled around the adjacent portion of the ring 4 as shown at 13. When formed in the manner described it will be seen that the supporting frame 1 is constructed from three pieces of wire rod bent and secured together in the manner described.

The frame 1 when constructed as described forms a support for the curtain of the hover, said curtain comprising a top section 14 in the form of a circular piece of suitable material having therein a central opening the edges of which are secured around the inner upper ring 2 while the outer edge of the top or upper portion of the curtain is secured to the ring 4 as shown. The upper portion or top 14 of the curtain preferably sags between the rings 2 and 4 for a purpose hereinafter described. The vertical portion 15 of the curtain which forms the side walls of the hover consists of a strip of material

of suitable width and having its upper end stitched to the upper portion 14 of the curtain adjacent to or just inside the ring 4 from which the portion 15 of the curtain 5 hangs down all the way around the ring and to within a short distance of the ground or floor on which the hover rests. The portion 15 of the curtain is slitted at intervals as at 16 to facilitate the passage of the 10 chicks through or under the same.

Arranged in the space inclosed by the rings 2 and 3 is a hot water receptacle or container 17 which may be of any suitable construction and which is here shown and 15 is preferably in the form of a jug or demijohn which is of sufficient height to project some distance above the upper ring 2 as shown. The jug or demijohn 17 is adapted to contain hot water which is the heat generating 20 medium of the hover. The chicks are prevented from coming into direct contact with the hot jug by a shield 18 formed of two or more thicknesses of suitable material arranged around the jug and secured 25 at their upper edges to the inner edge of the upper portion 14 of the curtain, as clearly shown in Fig. 3 of the drawings. When thus arranged the shield 18 will be disposed within the rings 2 and 3 of the curtain supporting 30 frame and will be supported by said frame around the jug. The shield 18 while protecting the chicks from direct contact with the jug 17 does not interfere with the proper radiation of the heat from the jug.

Arranged above the upper portion 14 of 35 the curtain and over the jug 17 is a heat retaining pillow 19 which consists of a casing formed of suitable fabric filled with any suitable heat retaining material such as fiber, 40 cotton batting or woolen rags. The pillow 19 may be of any suitable shape but is preferably circular and of sufficient size to engage and rest at its outer edges on the outer ring 4 of the supporting frame while the 45 center of the pillow is engaged with and supported by the upper end or head of the jug. When thus arranged the heat is retained by the pillow and will be evenly distributed through the hover. When it is 50 desired to refill the jug with hot water it is simply necessary to first remove the pillow, after which the jug may be readily lifted from the shield 18 and the cool water poured therefrom and the jug refilled and replaced 55 without disturbing any other parts of the hover or the chicks therein.

It has been found by experience that it is simply necessary to refill the jug twice a day preferably in the morning and again 60 in the evening. The heat radiating from the hot water in the jug and retained in the hover together with the natural heat from the bodies of the chicks is sufficient to keep the latter warm during the entire interval 65 between the changes of the water in the jug.

During the first week after the chicks are hatched and while they are still very delicate and have not learned where to get warm or how to enter or leave the hover, I preferably provide a chick retaining band 20 which 70 may be formed of roofing paper, cardboard, tin or other suitable material and which is in the form of a circular strip or band of sufficient diameter to slip readily over and inclose the vertical portion 15 of the curtain, 75 said band extending upwardly to near the top of said vertical portion of the curtain as clearly shown in Figs. 1 and 3 of the drawings. When thus arranged the band 20 will prevent the chicks from leaving the 80 hover and as soon as the chicks are of sufficient size or age may be readily removed to permit the chicks to pass in and out of the hover.

It will be understood that my improved 85 hover is to be used in a brooder or in a building or room of some kind where the same will be protected from the weather. The upper portion 14 of the curtain is preferably formed of a porous or loosely woven 90 material and is sagged as herein shown and described to permit insect powder to be placed thereon which will sift therethrough as the chicks pass beneath said upper portion of the curtain. The sag of this part of 95 the curtain is preferably sufficient to cause the heads of the chicks to come into engagement therewith as the chicks run back and forth beneath the same. This engagement of the heads of the chicks with the under 100 side of the upper portion 14 of the curtain will jar the latter, causing the powder to sift down onto the heads and bodies of the chicks, thus keeping the latter free from 105 lice.

While the hover has been hereinbefore described as being heated by hot water in a suitably arranged container, I may also heat the same with an equal degree of safety by means of electricity, which is preferably applied to the hover by means of an incandescent electric lamp 21, which is suspended in the space inclosed by the shield 18, and which has been previously described as being occupied by the jug 17. The modified form 110 of the invention is illustrated in Figs. 5 and 6 of the drawings, and by reference to these figures, it will be seen that the lamp 21 is suspended or supported in the space surrounded by the shield 18 by means of a cross 115 bar or strip 22 which is arranged centrally across the upper end of this space and is engaged with the upper edges of the shield or with the supporting ring 2. The bar 22 has formed in one edge a dove-tail shaped 120 notch 23, with which the socket or the conducting cord or wires of the lamp are engaged, said cord or wires having arranged thereon a short distance above the lamp a stop 24, which may be of any suitable con- 125 130

struction and is here shown in the form of a knob, which is adapted to engage the upper side of the bar or strip 22 when the wire or cord of the lamp is engaged with the 5 notch 23. When thus arranged the current conducting cord or wires pass out of the hover between the pillow 19 and the upper portion 14 of the curtain, while the lamp is suspended in the center of the space 10 surrounded by the shield, in which position the lamp will radiate sufficient heat to maintain the proper temperature in the hover.

From the foregoing description, taken in connection with the accompanying drawings, the construction and operation of the 15 invention will be readily understood without requiring a more extended explanation.

Various changes in the form, proportion and the minor details of construction may 20 be resorted to without departing from the principle or sacrificing any of the advantages of the invention, as claimed.

Having thus described my invention, what I claim is:—

25 1. A device of the character described comprising a wire supporting frame having upper and lower inner rings connected together and an upper outer ring connected to and supported from the inner upper ring, 30 a loosely woven fabric covering connecting the two upper rings and arranged to sag therefrom to provide an insect powder dispensing means, a heat disseminating element arranged centrally in the device, a shield 35 surrounding said element and connected to the two inner rings, a heat retaining pillow covering the entire device and supported by the two upper rings, said pillow having on 40 its bottom a depending annular portion to enter the sagged portion of said fabric covering to press the powder adapted to be contained therein.

2. A device of the character described comprising a wire supporting frame having 45 upper and lower inner rings connected together and an upper outer ring connected to and supported from said inner ring; an upper covering comprising an annular piece of fabric having its inner and outer edges 50 looped around said inner and outer upper rings and brought under and secured to the lower surface of said fabric, a vertically arranged shield placed within said upper and lower inner rings, comprising an outer band 55 having its upper end bent over the looped inner edge of said upper cover and a plu-

rality of inner bands fastened together and secured to the outer band, said bands having their lower ends fastened to said lower ring, a side wall formed by a circular strip of 60 fabric having its upper end bent over and secured to the outer edge of said upper covering, and a heat distributing member covering the entire device and supported by 65 said inner and outer rings. 65

3. A wire support for a hover composed of three pieces of wire, one piece being bent between its ends to form an upper inner cover supporting ring with ends projecting horizontally and vertically therefrom, the 70 second piece of wire having one end bent and secured to form a lower shield supporting ring and the opposite end thereof extended vertically to and horizontally from 75 said upper ring, said vertically extending members having their opposite ends secured at diametrically opposite points on said upper and lower rings, whereby said rings may be held in spaced and adjusted position, the third piece of wire being bent to form 80 an outer cover supporting ring, said ring having its end and central portion looped to form eyes adapted to receive the outer ends of said horizontally projecting members and the opposite end of said ring. 85

4. A device of the character described comprising a wire supporting frame having upper and lower inner rings connected together and an outer ring connected to and supported from the inner upper ring, an 90 electric lamp and conductor cord arranged within said upper and lower inner rings, a lamp supporting bar arranged diametrically across said upper inner ring and having in the center of one edge a dovetail shaped 95 notch, a stop bead slidably mounted on said conductor cord and adapted to be supported in said notch whereby the lamp is adjustably supported by said bar, a covering for the top and sides of the frame, a pillow 100 extending over the entire device and supported upper outer ring, and a shield arranged around and spaced from said electric lamp.

In testimony whereof I have hereunto set 105 my hand in presence of two subscribing witnesses.

FREDERICK W. HEIDELBACH.
